COMBINED CONTAINER AND CLEANER FOR ARTIFICIAL EYELASHES

Howard Aylott, Welwyn Garden City, England, assignor to Eylure Limited, Welwyn Garden City, England, a company of Great Britain

Filed July 12, 1965, Ser. No. 86,105

Term of patent 14 years

Claims priority, application Great Britain Apr. 21, 1965

(Cl. D86—10)

Fig. 1.

Fig. 2.

FIGURE 1 is a top plan view of a combined container and cleaner for artificial eyelashes showing my new design in open condition;

The outer surfaces of the top, bottom and sides of the box or container are planar in configuration.

I claim:

The ornamental design for a combined container and cleaner for artificial eyelashes, as shown and described.
